CIRCULATION SYSTEM OF PULP DIGESTERS

Ivan Penry Troëdsson, Tokyo, Japan; vested in
the Alien Property CustodianApplication May 1, 1940, Serial No. 332,711
In Japan April 20, 1939

2 Claims. (Cl. 92—7)

This invention refers to an improvement in circulation systems of pulp digesters at which a forced circulation of the mixture of pulp and liquid in the digester is obtained by means of a pump, placed in a pipe line connecting the lower and the upper parts of the digester, and at which a strainer for drawing off surplus liquid, and thereby keeping the liquid level constant, is arranged at the upper part of the digester.

The invention consists in arranging one or more rotary or oscillating bodies, such as propellers or similar devices, at the inlet of the suction part of the stated pipe line and close to the drawing-off strainer for the purpose of obtaining a uniform flow into the piping, and preventing the piping and the pump as well as the drawing-off strainer from being clogged and choked by the chips or the pulp.

The object of the invention is to make it possible to use forced circulation systems when cooking certain raw materials which have such a consistency that circulation by hitherto known arrangements is impossible. One such raw material is, for instance, bagasse. Such raw materials have a tendency to pack hard in the digester, and to form more or less large lumps which are liable to choke the circulation piping and cause the circulation to stop. They may also accumulate on the draw-off strainer so that it becomes impossible to draw off the surplus liquid. The present invention aims at removing operating difficulties of this kind.

The invention is schematically illustrated in vertical section in the attached drawing, in which 1 indicates the digester, 2 the circulation pump, 3 the suction pipe to the pump 2, 4 the pressure pipe from pump 2, 5 the rotary or oscillating body which is mounted on the shaft 6, and driven, for instance by the pulley 7 or in some other known way, 8 is the drawing-off strainer.

The mixture of pulp and cooking liquid is drawn by the pump 2 via the rotary body 5 into the suction pipe 3 in the upper part of the digester, and after passing the pump 2 is returned by way of the pressure pipe 4 into the lower part of the digester. The rotating body 5 breaks up any agglomerations of chips or pulp so that the flow into the suction piping becomes smooth and unobstructed. At the same time the rotary body 5 prevents any chips or pulp from settling on the drawing-off strainer 8.

The attached drawing shows only one way of

applying the invention. It is however possible also to apply the invention at such circulation systems where the circulating cooking liquid is separated from the pulp by means of a strainer placed before the suction pipe to the pump, and at which the practically fibre-free liquid only enters the circulation piping and the pump. At such circulating systems the strainer might gradually become choked with chips and pulp, but by using the rotary or oscillating body as described above the strainer can be kept clean, so that the circulation will work smoothly.

I claim:

1. A pulp digester comprising a tank having an upper outlet aperture and a lower inlet aperture, a tube secured to said tank and extending from the outlet aperture to the inlet aperture, whereby communication is established between the inside of said tank and the inside of said tube, a pump connected with said tube and adapted to draw the contents of said tank through said outlet aperture into said tube and feed the same through said inlet aperture back into said tank, movable means secured to said tank in proximity to said outlet aperture, said movable means comminuting the contents of the tank drawn into said outlet, and means for actuating said movable means, said tank being provided with a withdrawal aperture disposed above and in proximity to said outlet aperture, a strainer covering said withdrawal aperture and secured to the inside of said tank, said strainer being also disposed in proximity to said outlet aperture and said movable means, whereby the movable means simultaneously keeps said strainer unobstructed.

2. A pulp digester comprising a tank for containing a mixture such as pulp and liquid, means for withdrawing said liquid from the upper portion of said tank under a suction and for forcing the same back into the lower portion of the tank under pressure, said tank being provided with an overflow aperture disposed above and in proximity to said point of withdrawal, means for comminuting said mixture at said withdrawal point, filtering means covering said overflow aperture, said filtering means being also disposed in proximity to said comminuting means and said withdrawal point, whereby said comminuting means will also prevent pulp from accumulating upon said filtering means.

IVAN PENRY TROËDSSON.
